UNITED STATES PATENT OFFICE.

KATHARINE S. HANINGTON, OF WESTCHESTER, PENNSYLVANIA.

DESIGN FOR A SPOON.

SPECIFICATION forming part of Design No. 35,358, dated December 3, 1901.

Application filed August 30, 1901. Serial No. 73,879. Term of patent 14 years.

To all whom it may concern:

Be it known that I, KATHARINE S. HANINGTON, a citizen of the United States, residing at Westchester, in the county of Chester, State of Pennsylvania, have invented and produced a new and original Design for a Spoon; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a spoon embodying the present invention. Fig. 2 is a vertical transverse section through the bowl of a spoon embodying the present invention.

As shown in the drawings, the leading or material feature of my design consists in the specific shape of the bowl and its side flange, the bowl (shown at B) having its side edges in the form of outwardly-curved arcs of different radii, the edge of greater radius projecting from the longitudinal axis of the bowl

to a lesser extent than the edge of lesser radius. At the edge of the body of greater radius is the outwardly-directed flange C, extending throughout the length of the bowl and terminating at its forward end at the point of the bowl, the central portion of the flange being parallel with the longitudinal axis of the bowl, while the end portions of the flange are curved to the ends of the bowl, the flange being beveled throughout its length to the cutting edge D. Transverse sections of the bowl are longitudinal arcs of ovals. At one end of the bowl is the handle A.

Having thus described my invention, what I claim as new, and desire to secure by Letters Patent, is—

The design for a spoon, as herein shown and described.

In testimony whereof I affix my signature in presence of two witnesses.

KATHARINE S. HANINGTON.
